UNITED STATES PATENT OFFICE.

HARRISON D. KEMPTON, OF CRANSTON, RHODE ISLAND.

CARPET-BEATER.

1,241,222.

Specification of Letters Patent. Patented Sept. 25, 1917.

Application filed January 26, 1917. Serial No. 144,744.

To all whom it may concern:

Be it known that I, HARRISON D. KEMPTON, a citizen of the United States of America, residing at Cranston, in the county of Providence and State of Rhode Island, have invented a new and useful Carpet-Beater, of which the following is a specification.

My invention relates to improvements in portable, hand-operated machines for beating carpets and rugs for the purpose of liberating dust therefrom, and consists essentially of a supporting frame provided with means to convert the same into a truck by the mere act of tilting said frame backward, 10 and equipped with certain peculiar beater elements and with operating mechanism therefor, all as hereinafter set forth.

One object of my invention is to produce a comparatively light and inexpensive, 20 simply constructed and operated, and practicable and efficient machine, which is both portable and hand-operated, for beating carpets and rugs as they lie on the floor, or on the ground if it be preferred to do the work 25 out of doors, and by such beating liberate the dust and dirt from said carpets and rugs and so clean them in the most thorough manner.

Another object is to produce a carpet beater of this description that can most readily be converted into and used as a truck, for the moving about of carpets, rugs, and any other object or objects not too heavy or bulky, and as readily reestablished in its 30 position as and character of a carpet beater. 35 This feature may be utilized to advantage also whenever the machine is moved any appreciable distance, although said machine is so comparatively light that little difficulty is experienced in moving it while in 40 the upright position, or even in lifting and carrying the machine bodily.

Still another object is to provide such a machine with beating elements so arranged that they may have a certain amount of 45 lateral movement, hence are capable of actually striking, in a given number of pulsations, more of a given area than would be the case if said elements were restricted to unvarying planes of vertical movement.

50 Other objects and advantages will appear in the course of the following description.

I attain the objects and secure the advantages of my invention by the means illus-

trated in the accompanying drawings, in which—

Figure 1 is a rear elevation of a carpet beater which embodies a practical form of my invention; Fig. 2, a side elevation of said beater; Fig. 3, also a side elevation of said beater, but showing the same in position to serve as a truck, or ready to be pushed or drawn about on its wheels, and, Fig. 4, a top plan of the base of the frame and the beater elements, the uprights of said frame being in cross section and the operating rods 60 omitted.

Similar reference characters designate similar parts throughout the several views.

In the embodiment of the invention herein disclosed, a supporting frame, for the 70 instrumentalities of the beater, consists of a base made up of horizontal, parallel, side pieces 1—1 connected by a cross piece 2, and a stand made up of uprights 3—3 rising from said base pieces and terminating at 75 their upper ends in handles 4—4, and connected below said handles by a cross rod 5, the frame as now described being assumed to be in its erect position.

The uprights 3 are attached to the base 80 pieces 1 at the front ends of the same, and wheels or rolls 6—6 are mounted at the rear ends of said base pieces, at 7—7, said base pieces being slotted at 8—8 to accommodate said rolls.

Loosely pivoted at 9—9 to the uprights 3, against the outer sides thereof, are two leg members 10. Normally the members or legs 10 hang against the outer faces of the uprights 3, as best shown in Fig. 2, but when 90 the frame is tilted backward, in the manner and for the purpose presently to be more fully explained, said legs swing on their pivots 9 clear of said uprights, except the upper ends of said legs, of course, or rather 95 the uprights pass away from the major portions of the legs, which latter always maintain an approximately vertical position. The uprights 8 are provided above or behind the legs 10, according to the position 100 of said uprights, with stops 11—11 for said legs, which stops limit the backward swing of said legs, when said uprights are down in truck-forming position, as represented in Fig. 3.

Bracketed at 12—12 at the front ends of

the base pieces 1, or at the junctions of the uprights 3 with said base pieces, is a rod 13, and mounted to rock and also for lateral movement on said rod is a plurality of resilient beating elements 14, each consisting in the present case of a wire bent around the rod and extending in both directions therefrom. That is to say, each element or wire 14 extends both forwardly and rearwardly from the rod 13, but the forwardly-extending portion is long, the same being the part that is applied to the carpet or rug in the beating operation, while the rearwardly-extending portion is short. There are here present six of the wires 14, although their number may vary, and these six wires are divided into two groups, of three each, by having their rear ends connected with the two rods 15 arranged parallel with the rod 13. Each rod 15 has flanges 16-16 at the ends to prevent said rod and the wires 14 connected therewith from becoming disengaged. The wires 14 and the rods 15 are loosely connected, so that a wide range of independent, relative movement, lateral and endwise respectively, is permitted thereto. The middle wire 14 of each group is continued rearwardly beyond the rod 15 which assists in forming such group, such rearwardly-extending part being represented at 17. Spaces 18 may or may not be placed on the rod 13 between the wires 14, and, if such spacers be used, they should not be sufficiently wide to prevent a considerable degree of lateral movement on the part of said wires. The front ends of the rods 14 may be bent over, substantially as represented at 18, so that said ends will not catch in the nap or fiber of the carpet or rug being beaten, or injure such nap or fiber.

The wires 14 are of a size and character (being resilient) that fits them especially for the purpose for which they are used.

In Fig. 3 the upper (forward) terminal portions of the wires 14 are broken off, and in Fig. 4 a corresponding portion of one of such wires is also broken off.

Journalled in the uprights 3 below the cross rod 5 is a crank-shaft 19. There are oppositely-directed cranks 20 in the crank-shaft 19, and a connecting-rod 21 extends from each of said cranks to the part 17 of the wire 14 that is in the same or approximately the same vertical plane with the crank. A pinion 22 is secured on one end of the crank-shaft 19, and mounted on a stud 23, which is set in one of the uprights 3 above the pinion 22, is a driving gear 24. The gear 24 intermeshes with the pinion 22, and is provided with a crank handle 25.

It is desirable to provide some means for adjusting the stroke of the beating elements or wires 14 to different thicknesses of carpets and rugs, and such means may be afforded by making each connecting-rod 21

in two sections and introducing a turn-buckle 26 into the structure, adjacent terminals of such sections being screw-threaded for engagement with said turn-buckle. When the beater is applied to a thin carpet or rug, the turn-buckles 26 are, if necessary, adjusted to shorten the connecting-rods 21, of which said turn-buckles form parts, so that the free front terminal portions of the wires 14 will be caused to deliver their blows close to the floor or ground, and, when said beater is applied to a thick carpet or rug, said turn-buckles are, if necessary, adjusted to lengthen said connecting-rods, so that said terminal portions deliver their blows on a horizontal plane that is above the horizontal plane on which the blows are delivered in the first instance.

In practice, the beater is first placed in upright position on a carpet or rug, and then the operator, standing behind with one or both feet on the cross piece 2, which is also a foot piece, and one hand grasping one of the handles 4, to hold the apparatus in position and steady the same, grasps the crank handle 25, with the other hand, and revolves the gear 24. The revolving gear 24 causes the pinion 22 to revolve and with it the crank-shaft 19, thus imparting to the wires 14 a vibratory or oscillatory motion, through the medium of the cranks 20, connecting-rods 21, projections 17, and rods 15. Each connecting-rod 21 operates one of the two groups of connected wires 14, and such groups rock on the rod 13 in opposite directions, owing to the relative setting of the cranks 20, so that when the free, front terminals of the wires in one group rise the corresponding terminals of the wires in the other group descend, and vice versa. The action of the machine is more evenly balanced by arranging the two groups of wires to oscillate in opposite directions simultaneously, than would be the case if they both oscillated simultaneously in the same direction. The central wire 14 in each group, which is directly actuated by the attached connecting-rod 21, carries with it the other two wires 14 in that group, through the medium of the rod 15 which completes said group.

As the wires 14 are vibrated they shift their positions laterally more or less on the rods 13 and on or with the rods 15, this being true of the outside wires in each group more especially, consequently practically all parts of that portion of the carpet or rug that is under the beating elements are struck by the latter. The cleaning operation is, therefore, more thorough than it would be if the aforesaid elements had no lateral movement.

After that portion of the carpet or rug which is under the beating elements has been sufficiently cleaned, the beater is moved to

leave said elements over another portion of said carpet or rug, and so on until the entire surface has received the necessary attention.

5. When the beater is to be moved any considerable distance, it is usual to grasp the handles 4 and tilt said truck backward until it rests on the wheels 6, and then to push or pull the beater along on said wheels, some 10 what after the manner of wheelbarrow. In this way the beater can be moved about very conveniently and with the expenditure of very little strength.

In the event it be desired to convey a carpet or pile of rugs, for example, or it might be one or more objects or articles of a different character, from one locality to another, the beater is tilted backward and permitted to rest on the wheels 6 and the legs 10, as 20 illustrated in Fig. 3. The truck thus formed is next loaded, then the handles 4 are grasped and elevated until the legs 10 clear the floor or ground, and said truck with its load is pushed or pulled to the new locality, 25 where said truck is again permitted to rest in part on said legs, and the load is removed. When the beater is tilted into truck-forming position, the then upstanding wires 14 or the long portions thereof form a back for 30 the pseudo truck.

Upon tilting the machine into the former or initial position, with the base pieces 1 resting on the floor or ground, said machine is ready again to be operated for beating 35 purposes. Said machine may also be so operated, when in the tilted or turned-down position, by being pushed against a carpet or rug that is hung on a line or otherwise vertically disposed, or against a suspended portion.

40 40. Upon tilting the machine into the former or initial position, with the base pieces 1 resting on the floor or ground, said machine is ready again to be operated for beating purposes. Said machine may also be so operated, when in the tilted or turned-down position, by being pushed against a carpet or rug that is hung on a line or otherwise vertically disposed, or against a suspended portion.

It is clearly to be seen that the beating elements, when the beater is disposed as in Fig. 3, will be oscillated, upon rotating the gear 24, in the same manner as said elements 45 are oscillated when disposed as in the other views.

In turning down the beater the legs 10 naturally assume the supporting position shown in Fig. 3, where said legs are in contact with the stops 11 and are held thereby at a slant away from the base pieces 1, which slant is sufficient to prevent said legs from accidentally swinging away from said stops and out of said supporting position. And in 55 turning up the beater the legs naturally assume their inactive position alongside of the uprights.

In practice the crank-shaft is revolved quite rapidly and this produces the desired 60 whip-like action on the part of the beating elements.

Instead of wire for the beating elements, suitable wooden rods may be used, and the beater frame may be made of either wood as 65 shown, or metal, or of both.

Various changes in the shape, size, construction, and arrangement of some or all of the parts of my beater may be made without departing from the scope of the invention as defined by the appended claims. 70

What I claim as my invention, and desire to secure by Letters Patent, is—

1. The combination, in a carpet beater, with a frame comprising a base and a stand joined to said base at one end of the latter, anti-friction means at the other end of said base, and a supporting member arranged to swing from said stand, the construction and arrangement of parts being such that said frame can be tilted from a vertical to a 80 horizontal position onto such anti-friction means, and can be permitted to rest on said anti-friction means and said supporting member, of beating elements mounted in said frame, and operating mechanism, carried by said frame, for said beating elements.

2. The combination, in a carpet beater, with a frame comprising a base and a stand connected with said base at one end of the latter, anti-friction means at the other end of said base, legs pivotally attached to said stand, and stops arranged on said stand in the path of said legs when in operative position, the construction and arrangement of 95 parts being such that said frame can be tilted from a vertical to a horizontal position onto said anti-friction means, and can be permitted to rest on said anti-friction means and said legs, of beating elements 100 mounted in said frame, and actuating mechanism, carried by said frame, for said beating elements.

3. The combination, in a carpet beater, with a frame provided with a supporting 105 rod, a plurality of beating elements mounted for oscillatory and lateral movement on said rod, and a rod loosely connecting the rear terminals of said beating elements, of means to oscillate said elements as a group, said 110 means being carried by said frame.

4. The combination, in a carpet beater, with a frame provided with a supporting rod, a plurality of beating elements mounted for oscillatory and lateral movement on 115 said rod, and rods loosely connecting the rear terminals of said beating elements and dividing said elements into groups, of means adapted to oscillate such groups independently, said means being carried by said 120 frame.

5. The combination, in a carpet beater, with a frame provided with a supporting rod, and equipped with operating mechanism, said mechanism consisting in part of 125 connecting-rods, of a plurality of beating elements mounted for oscillatory and lateral movement on said rod, and rods loosely connecting the rear terminals of said beating elements and separating said elements into 130

groups, each of said connecting-rods operatively engaging one of the beating elements in each group.

6. The combination, in a carpet beater, 5 with a frame provided with a supporting rod, a plurality of beating elements mounted for oscillatory and lateral movement on said rod, and a rod loosely connecting the rear terminals of said beating elements, of mechanism to oscillate said elements as a group, 10 said mechanism being carried by said frame, and consisting in part of means to vary the stroke of said group of beating elements.
7. The combination, in a carpet beater, 15 with a frame provided with a supporting rod, operating mechanism carried by said frame, said mechanism consisting in part of connecting-rods which are adjustable as to length, of a plurality of beating elements mounted for oscillatory and lateral movement on said rod, and rods loosely connecting 20 the rear terminals of said beating ele-

ments and separating them into groups, each of said connecting-rods operatively engaging one of the beating elements in each group. 25

8. The combination, in a carpet beater, of a frame consisting of a base made up of side pieces and a connecting foot piece, and of a stand made up of uprights rising from the front ends of said side pieces and a connecting member, wheels mounted at the rear ends of said side pieces, a rod supported by said frame, a plurality of beating elements mounted on said rod, and projecting beyond 30 said uprights and the adjacent ends of said side pieces, a crank-shaft journaled in said uprights and operatively connected with said beating elements, and means carried by said uprights to revolve said crank-shaft. 35
